J. SOSS

METHOD OF MANUFACTURING HINGE BUTTS

Filed Oct. 16, 1922

UNITED STATES PATENT OFFICE.

JOSEPH SOSS, OF BROOKLYN, NEW YORK.

METHOD OF MANUFACTURING HINGE BUTTS.

Application filed October 16, 1922. Serial No. 594,781.

To all whom it may concern:

Be it known that I, JOSEPH Soss, a citizen of the United States, and residing at Brooklyn, in the county of Kings and State of New York, have invented certain new and useful Improvements in Methods of Manufacturing Hinge Butts, of which the following is a specification, such as will enable those skilled in the art to which it appertains to make and use the same.

This invention relates to hinge butts, and particularly to the method of manufacturing hinge butts, such as shown and described in a prior application filed by me June 28, 1922, Ser. No. 570,446; and the object of the invention is to produce a strong and durable hinge butt of the class described in a simple and effective manner from suitably fashioned sheet metal parts, assembled to form a hinge butt as hereinafter described and claimed.

The invention is fully disclosed in the following specification of which the accompanying drawing forms a part in which the separate parts of my improvement are designated by suitable reference characters in each of the views, and in which:—

Fig. 1 is a plan view of a hinge butt made according to my invention.

Fig. 2 is a partial section on the line 2—2 of Fig. 1.

Fig. 3 is a perspective view of one of the hinge butts shown in Fig. 1 made according to my improved method.

Fig. 4 is a plan view of one blank from which my improved hinge butt is formed.

Fig. 5 is a side edge view showing the first step in fashioning the blank shown in Fig. 4.

Fig. 6 is a section on the line 6—6 of Fig. 5 showing another step in the formation of the blank shown in Fig. 4.

Fig. 7 is a view similar to Fig. 5 and showing the next step.

Fig. 8 is a perspective view of another blank from which my improved hinge butt is formed.

Fig. 9 is a side edge view of the blank shown in Fig. 8 and showing the next step in the operation of fashioning the same.

Fig. 10 is a sectional view similar to Fig.

9 showing the next step in the operation of fashioning the blank shown in Fig. 8; and,

Fig. 11 is a sectional view through both of the fashioned blanks shown in Figs. 7 and 10, assembled; and,

Fig. 12 is a section on the line 12—12 of Fig. 11 showing the last step in forming my improved hinge butt.

In Figs. 1 and 2 of the accompanying drawing, I have shown a complete hinge 60 formed by separate hinge butts 16 and 17 joined together by a pivot pin 18 in the usual manner, but my invention relates specifically to the method of forming the hinge butt 16, and in carrying my invention into effect, I provide two sheet metal blanks 19 and 20 shown in Figs. 4 and 8 respectively, the blank 19 being composed of comparatively thin sheet metal, while the blank 20 is composed of heavier sheet metal, and 65 is used as a filler for the blank 19 when fashioned to the desired form, and the blank 19 forms a casing or jacket for the filler formed from the blank 20.

The blank 19 is substantially elongated 75 and rectangular in form and is provided at the opposite sides thereof adjacent to the end portion 19^a thereof with lateral extensions 19^b, and said end of the blank is slightly contracted as shown at 19^c, and in the production of a hinge butt, the blank 19 or the end portion 19^a thereof is first fashioned to form a substantially hook-shaped end 19^d having top and bottom integral and substantially circular plates or flanges 19^e and in this step of the operation, it will be noted that the drawn metal will be slightly ragged at its edges as indicated in Fig. 5.

The next step in fashioning the blank 19 consists in bending the side edges of the blank 19 inwardly to form flanges 19^f as shown in Fig. 6 of the drawing, and indicated in dotted lines in Fig. 5 of the drawing, after which the blank thus formed is placed in a finished forming die to complete 90 the proper formation of the blank 19, after which the ragged edges are trimmed as shown at 19^g in Fig. 7 of the drawing, and the plates or flanges 19^e are pierced or drilled to form apertures 19^h to receive the 95 100

pivoted pin 18, and it will be noted that a slight shoulder 19¹ is formed in the above finishing and trimming operation.

The blank 20, from which the other part 5 of my improved hinge butt is formed, is cut at the end portion 20^a thereof to form two elongated apertures 20^b forming three projecting fingers or arms 20^c, the ends of which are slightly curved and preferably 10 rounded as shown at 20^d. After the blank 20 has been formed in the manner above set out, and by the use of suitable dies, the fingers or arms 20^c thereof are fashioned to form substantially circular pin receiving 15 knuckles 20^e as shown in Fig. 9 of the drawing, after which the blank is broached as shown at 20^f in Fig. 10 of the drawing, and the formation thereof is completed to permit of its insertion into and assemblage with 20 the fashioned blank 19 shown in Fig. 7 of the drawing.

The next step in forming my improved hinge butt consists in placing the complete blank 20 formed as shown in Fig. 10 within 25 the complete blank 19 shown in Fig. 7 of the drawing in the manner illustrated in Fig. 11, with the knuckles 20^e of the blank 20 within the hook-shaped portion 19^a of the blank 19, and the separate parts are pressed 30 or fit together by the use of suitable dies, after which said parts are welded or otherwise secured together, as shown at 21 in Fig. 11 of the drawing, and the screw holes or 35 apertures 22 are punched or drilled therein and countersunk as shown in Fig. 11.

It will be noted that the flanges 19^f of the blank 19 project slightly beyond the face of the blank 20 as shown in Fig. 11 of the drawing, and in the finishing operation of 40 the complete hinge butt, the projecting portions of the flanges 19^f are pressed inwardly to lie flush with the face of the fashioned blank 20 as shown in Fig. 12, and this operation may be performed before or after 45 the parts have been welded or otherwise secured together.

It will be noted that the separate operations of forming the separate parts of my improved hinge butt as herein set out may 50 be produced in one or more operations in a suitable machine and by the use of suitable dies as for example, the substantially hook-shaped portion of the blank 19, while being described as formed in a single operation, 55 may be formed in one or more successive operations in order that the metal will not be strained or ruptured in accomplishing the desired result and as this is the common practise in the art of fashioning sheet metal 60 parts by the use of dies or other forming tools, it is not deemed necessary to specify the specific steps of the process, and while I have shown a hinge butt of specific formation and design, it will be noted that my 65 invention is not necessarily limited in this

respect and various changes in and modifications of the method of manufacturing hinge butts herein shown and described, may be made within the scope of the appended claims without departing from the spirit of my invention or sacrificing its advantages.

Having fully described my invention, what I claim as new and desire to secure by Letters Patent, is:—

1. The herein described method of manufacturing hinge butts, which consists in providing two sheet metal blanks, shaping one of said blanks to form a substantially hook-shaped end portion having top and bottom flanges, and flanges extending longitudinally of the opposite sides of said blanks, shaping one end portion of the other of said blanks to form a plurality of projecting fingers, fashioning said fingers to form substantially circular knuckles and securing the separate fashioned blanks, together with the knuckles of the last named blank, within the hook-shaped portion of the first named blank.

2. The herein described method of manufacturing hinge butts, which consists in providing two sheet metal blanks, shaping one of said blanks to form a substantially hook-shaped end portion having top and bottom flanges, and flanges extending longitudinally of the opposite sides of said blanks, shaping one end portion of the other of said blanks to form a plurality of projecting fingers, fashioning said fingers to form substantially circular knuckles and securing the separate fashioned blanks, together with the knuckles of the last named blank, within the hook-shaped portion of the first named blank, and with the flanges of the first named blank overlapping the sides of the last named blank, and forming screw apertures in the body portion of the hinge butt thus formed.

3. The herein described method of manufacturing hinge butts, which consists in providing two sheet metal blanks, one of said blanks being provided at one end with lateral extensions, and the other of said blanks being provided at one end with projecting fingers, shaping the end portion of the first named blank provided with the laterally directed extensions, to form a substantially hook-shaped end portion having top and bottom flanges, and shaping the fingers of the other blank to form substantially circular knuckles, and said blanks being adapted to be placed one upon the other with the knuckles of the last named blank within the hook-shaped end portion of the first named blank and secured together to form a hinge butt.

4. The herein described method of manufacturing hinge butts, which consists in providing two sheet metal blanks, one of said blanks being provided adjacent to one

end portion thereof with laterally directed extensions, first shaping said end portion to form a substantially hook-shaped end portion having top and bottom flanges, shaping the side edges of said blank to form longitudinal flanges, which join said first named flanges, forming apertures in said first named flanges, trimming and finish forming said blank, fashioning the other of said blanks to form at one end portion thereof a plurality of substantially circular knuckles, placing the last named blank within the first named blank thus formed, and securing the separate blanks together to form a hinge butt.

5. The herein described method of manufacturing hinge butts, which consists in providing two sheet metal blanks, one of said blanks being provided adjacent to one end portion thereof with laterally directed extensions, first shaping said end portion to form a substantially hook-shaped end portion having top and bottom flanges, shaping the side edges of said blank to form longitudinal flanges, which join said first named flanges, forming apertures in said first named flanges, trimming and finish forming said blank, fashioning the other of said blanks to form at one end portion thereof a plurality of substantially circular knuckles, placing the last named blank within the first named blank thus formed, securing the separate blanks together to form a hinge butt, and compressing the side flanges of said first named hinge butt.

6. The herein described method of manufacturing hinge butts, which consists in providing two sheet metal blanks, one of said blanks being provided adjacent to one end portion thereof with laterally directed extensions, first shaping said end portion to form a substantially hook-shaped end portion having top and bottom flanges, shaping the side edges of said blank to form longitudinal flanges, which join said first named flanges, forming apertures in said first named flanges, trimming and finish forming said blank, fashioning the other of said blanks to form at one end portion thereof a plurality of substantially circular knuckles, placing the last named blank within the first named blank thus formed, securing the separate blanks together to form a hinge butt, compressing the side flanges of said first named hinge butt, and forming screw apertures in the hinge butt thus formed.

7. The herein described method of manufacturing hinge butts, which consists in providing two sheet metal blanks of different thicknesses, one of said blanks being thinner than the other and provided adjacent to one end portion thereof with laterally directed extensions, first fashioning said end portion to form a substantially hook-shaped end

portion having top and bottom flanges, fashioning the side edges of said blank to form longitudinal flanges, which join said first named flanges, forming apertures in said first named flanges, trimming and finish forming said blank, the other of said blanks being heavier than the first named blank and provided at one end portion with a plurality of fingers, fashioning the fingers to form substantially circular knuckles, placing the last named blank thus formed within the completed first named blank with the knuckles of the last named blank within the hook-shaped portion of the first named blank, and securing said blanks together to form a hinge butt.

8. The herein described method of manufacturing hinge butts, which consists in providing two sheet metal blanks of different thicknesses, one of said blanks being thinner than the other and provided adjacent to one end portion thereof with laterally directed extensions, first fashioning said end portion to form a substantially hook-shaped end portion having top and bottom flanges, fashioning the side edges of said blank to form longitudinal flanges, which join said first named flanges, forming apertures in said first named flanges, trimming and finish forming said blank, the other of said blanks being heavier than the first named blank and provided at one end portion with a plurality of fingers, fashioning the fingers to form substantially circular knuckles, placing the last named blank thus formed within the hook-shaped portion of the first named blank, and securing said blanks together, by spot welding, to form a hinge butt.

9. The herein described method of manufacturing hinge butts, which consists in providing two sheet metal blanks of different thicknesses, one of said blanks being thinner than the other and provided adjacent to one end portion thereof with laterally directed extensions, first fashioning said end portion to form a substantially hook-shaped end portion having top and bottom flanges, fashioning the side edges of said blank to form longitudinal flanges, which join said first named flanges, forming apertures in said first named flanges, trimming and finish forming said blank, the other of said blanks being heavier than the first named blank and provided at one end portion with a plurality of fingers, fashioning the fingers to form substantially circular knuckles, placing the last named blank thus formed within the hook-shaped portion of the first named blank, securing said blanks together by spot welding to form a hinge butt, and forming screw apertures in said hinge butt.

10. The herein described method of manufacturing hinge butts which consists in providing two sheet metal blanks, shaping one of said blanks to form a substantially

hook-shaped end portion having top and bottom flanges, fashioning the end portion of the other of said blanks to form a substantially circular bearing knuckle or 5 knuckles and securing the separate fashioned blanks, together with the bearing knuckle or knuckles of the last named blank,

within the hook-shaped portion of the first named blank.

In testimony that I claim the foregoing as 10 my invention I have signed my name this 13th day of October, 1922.

JOSEPH SOSS.
